F. L. MARTIN

COMBINATION PAN AND SIFTER

Filed July 10, 1923

INVENTOR
Frank L. Martin,

By *P. A. Tamm Talbot*
ATTORNEY

UNITED STATES PATENT OFFICE.

FRANK L. MARTIN, OF DUNBAR, PENNSYLVANIA.

COMBINATION PAN AND SIFTER.

Application filed July 10, 1923. Serial No. 650,630.

To all whom it may concern:

Be it known that FRANK L. MARTIN, a citizen of the United States of America, residing at Dunbar, in the county of Fayette and State of Pennsylvania, has invented new and useful Improvements in Combination Pans and Sifters, of which the following is a specification.

The object of the invention is to provide a device particularly adapted for use in connection with open grates and designed as a means for receiving the coal and ashes dropped from the grate so that the ashes may be deposited in a suitable receptacle and unburnt coal thereafter returned to the grate.

With this general object in view the invention consists in a construction and combination of parts of which a preferred embodiment is shown in the accompanying drawings, wherein:—

Figure 1 is a perspective view showing an open grate and the manner in which the invention is used in connection therewith.

Figure 2 is a perspective view of the ash receptacle.

Figure 3 is a perspective view of the sifter and coal catcher.

Figure 4 is a perspective view of a carrier by means of which the ash receptacle is transported.

The invention is designed for use in connection with an open grate such as that indicated at 1 in Figure 1 of the drawings and comprises a lower member or ash receptacle 2 and an upper member or sifter and coal catcher 3, the two members being correspondingly dimensioned in plan and an upper member 3 being supported above the lower member 2 on rods 4 transversely spanning the latter adjacent the ends. The lower member or receptacle is open at the top as is also the upper member or coal catcher 3 but the latter is provided with a per-

forated or foraminated bottom 5 through which ashes may readily pass. Both members 2 and 3 are provided with handles 6, the handle on the latter being designed to permit of its being reciprocated or oscillated over the member 2 by a simple shifting back and forth on the rods 4 by which it is supported above the receptacle 2. As the ashes are deposited from the grate, they fall in the catcher or sifter 3, as do also coals which fall before having been converted to ashes or cinders. The simple reciprocation of the member 3 will sift the ashes from the coals into the receptacle 2, when the member 3 may be withdrawn and the coals dumped back on the grate, after which the receptacle 2 may be withdrawn from its position in the fireplace and removed to dispose of its contents of ashes.

To permit of ready transportation of the receptacle 2, the handle member or bail 7 is provided, the hooks 8 at the extremities of which are adapted for engagement with the offsets 9 formed at intermediate points in the transverse rods 4, constituting seats 70 for the hooked ends of the bail which is readily detachable from the receptacle when the latter is replaced in its position in the fireplace.

Having described the invention, what is claimed as new and useful is:—

A device for the purpose indicated comprising an ash pan or receptacle open at its top and provided with transverse bars spanning its forward and rear walls adjacent its ends, and a coal catcher and ash sifter dimensioned according to the receptacle and provided with a foraminated bottom resting on said rods for reciprocating movement longitudinally thereof.

In testimony whereof he affixes his signature.

FRANK L. MARTIN.
